2 Sheets-Sheet 2

UNITED STATES PATENT OFFICE.

RAYMOND S. HILL, OF MINNEAPOLIS, MINNESOTA.

CARBURETOR.

Application filed January 23, 1919. Serial No. 272,639.

To all whom it may concern:

Be it known that I, RAYMOND S. HILL, a citizen of the United States, residing at Minneapolis, in the county of Hennepin and 5 State of Minnesota, have invented certain new and useful Improvements in Carburetors; and I do hereby declare the following to be a full, clear, and exact description of the invention, such as will enable others 10 skilled in the art to which it appertains to make and use the same.

My invention relates to carburetors for internal combustion engines, and has for its object to simplify the construction and 15 improve the operation thereof. This carburetor is of a type wherein the air is pre-heated, in part, before it is delivered to the manifold. The hydrocarbon liquid is taken up by the air that is to be preheated and the 20 initial vaporization is insured by the heat afforded by the exhaust from the engine.

A carburetor involving the above noted features, and others, is illustrated in the accompanying drawings, wherein like characters 25 indicate like parts throughout the several views.

Referring to the drawings,

Fig. 1 is a side elevation showing the carburetor applied to a multicylinder internal combustion engine;

Fig. 2 shows the carburetor partly in section on the line 2—2 and partly in section on the line 2^a—2^a of Fig. 3; and

Fig. 3 is a fragmentary horizontal section 25 on the line 3—3 of Fig. 2, and Fig. 4 is a fragmental horizontal sectional on the line 4—4 of Fig. 2.

Of the parts of the engine, it is only desirable to note the cylinder casting 4, the 40 intake manifold 5 and the exhaust manifold 6, which parts are of the standard or any suitable construction.

The carburetor proper is a self-contained structure and comprises the tubular mixing chamber 7 having a contracted portion adjacent its lower end, the float chamber 8, and air intake elbow 9. The mixing chamber 7 has a flanged upper end adapting it to be secured to the intake manifold 5 in 45 the customary way, and it contains the customary throttle valve 10. The lower

portion of the chamber 7 is provided with a partition 11 which has a depending nut-equipped stem that supports an annular valve-seating plate 12. The periphery of the 55 plate 12 is spaced from the surrounding wall of the carburetor and normally supports an annular gravity-seated air intake valve 13. Spaced inward from the valve 13, the plate 12 has a raised hub 14 which 60 serves to keep a constant air passage or clearance between the valve and hub, regardless of the distance that said valve may be raised in the air intake action. The stem depending from partition 11 is connected 65 to the lower portion of chamber 7 by a partition 11 having spaced holes 11^a therethrough forming air passages. The chamber 7 has a contraction at its lower end slightly above the partition 11. As the 70 engine is in operation there may be some condensation of the liquid fuel on the walls of the intake passage. If so, this liquid would have a tendency to drip off the inner edge of said contraction into the ingoing air 75 stream, so that it would be more readily picked up by the air stream than would be the case if the liquid adhered to the walls of the intake passage.

The improved carburetor has been especially designed for heating and vaporizing kerosene or hydro-carbons heavier than gasoline. The kerosene will be carried in a suitable tank and, in any of the well known means, will be delivered to the float 80 chamber 8 through a supply pipe 15 shown as coupled to a nipple 16 projected from one side of said chamber 8. The port in the tubular nipple 16 is adapted to be opened 85 and closed to the desired extent by the customary valve 17.

The level of the kerosene in the float chamber 8 is indicated by the dotted line z—z. The chamber 8 is provided at one side with a projected portion 8^a that is 90 formed with a vertical passage 18, the lower portion of which is contracted at 18^a. A zigzag oil delivery conduit 19 connects the interior of the float chamber 8 to the passage 18. This conduit 19 is adapted to be opened 95 and closed to any desired extent by a suitable needle valve 19^a. The receiving end 100

of said conduit 19 is below the liquid level 2—2 but the delivery end thereof into the passage 18 is above said liquid level. By reference to Fig. 2 it will be noted that the 5 said delivery end of the conduit 19 is above the contracted lower extremity 18^a of the passage 18, this being done for a purpose which will presently appear.

The upper extremity of the passage 18 10 is connected to the receiving end of a pipe 20, as shown, by means of a coupling head 21 and cap screws 22. This pipe 20 has an intermediate portion that is subject to the heat from the exhaust manifold 6 of the 15 engine, and preferably and, as shown, it is formed with a coiled portion 23 contained in the housing 24 that is bolted, or otherwise detachably secured directly on said exhaust manifold 6. The other end of said pipe 20 20 is connected to an elbow 25 that delivers into the mixing chamber 7 through a port 26 in one side of the latter, said elbow being detachably secured to the body casting of the carburetor by cap screws 27.

25 Working within the float chamber 8 is a float 28 which operates the valve 17, in the usual way, to maintain a constant level of the kerosene in the said chamber. The operation of this improved carburetor is substantially as follows:

When partial vacuum or suction is produced in the main chamber 7 by the piston movement, the valve 13 will be raised to permit air to be drawn into said mixing chamber through the air intake elbow or member 9, and such partial vacuum or suction will also produce a partial vacuum in the pre-heating pipe 20. When a partial vacuum is produced in the said pipe 20, air will, of course, be drawn into the said pipe due to 40 passage 18 and this contracted port 18^a. In view of the contraction 18^a a partial vacuum or suction will be produced in the kerosene delivery conduit 19 and kerosene will be drawn from the float chamber 8 and will be caused to overflow against the wall of the 45 passage 18. The upwardly moving current of air in passage 18 and pipe 20 will carry the kerosene with it as fast as it is drawn from conduit 19. The fuel entering passage 50 18 through opening 19 is in part distributed on the walls of said passage. The vaporization of the fuel will be assisted by the heated walls on which it is thinly spread. The 55 kerosene-laden air in preheated condition will be delivered into the mixing chamber 7 where it will be mixed with the additional or main supply of air which is drawn in through the elbow 9. Thus, good evaporat- 60 ion and thorough mixing of kerosene and air is accomplished before the explosive vapor is introduced into the intake manifold of the engine.

65 The contraction 18^a at the lower end of the passage 18 insures a good current of air

into tube 20 and affords a shoulder against which any surplus kerosene will lodge, and by which it will be delivered into direct contact with air that is drawn rapidly through the said contraction, and in this way, any 70 kerosene not taken up by the upwardly moving air at an earlier time will be caught before it can drip down through the said contraction 18^a.

In this carburetor, the pipe 20 and passage 18 with the connections constitute what may be properly designated as a primary air intake passage, and the air passage through the elbow 9 may be treated as a valve-controlled auxiliary air intake passage. 75

This carburetor is especially designed for heating and vaporizing kerosene or hydrocarbons heavier than gasoline, and in such use, it will, of course, be understood that 80 gasoline may be used to start the engine into action, this being a well known practice. 85

What I claim is:

1. A carburetor for internal combustion engines provided with a mixing chamber, a valve-controlled air inlet at the bottom thereof, an air inlet conduit communicating with said chamber at an intermediate portion thereof, said conduit communicating with an air intake spaced from said mixing chamber and comprising a vertical cylindrical passage having a contracted lower end through which air enters, a liquid fuel supply chamber having a delivery conduit opening into said cylindrical passage through the vertical wall thereof and terminating flush with said wall at a point above the contracted lower end of said passage, and a throttle valve located adjacent the discharge end of said mixing chamber and serving to simultaneously control the suction through said valve controlled air inlet and through said second mentioned air inlet. 90 95 100 105

2. A carburetor for internal combustion engines provided with a mixing chamber, a float chamber, a valve controlled air inlet at the bottom of said mixing chamber, a constantly opened air inlet comprising a passage located at one side of said float chamber forming an air intake conduit and having a contracted opening at its lower end, a fuel intake passage opening into said passage and terminating flush with the wall thereof above the contracted opening and a conduit connected to said vertical passage and leading therefrom into the intermediate portion of said mixing chamber. 110 115 120

3. A carburetor for internal combustion engines provided with a mixing chamber, a throttle valve therein, a float chamber, a cylindrical passage at one side of said float chamber having an air intake conduit connected at its upper end, said passage having a contracted opening forming a shoulder at its lower end, a fuel intake passage having 125 130

its receiving end below the level of the fuel in the float chamber and its delivery end above the level of the fuel and opening into the said passage and terminating flush with the wall thereof above the contracted opening therein, said vertical cylindrical passage being connected at its upper end to an exhaust heated tube, said tube communicating

at its other end with the mixing chamber below the throttle valve.

In testimony whereof I affix my signature in presence of two witnesses.
